UNITED STATES PATENT OFFICE.

FRANK J. ARNOLD, OF BROOKLYN, NEW YORK.

DESIGN FOR A BUTTON.

Application filed January 19, 1926. Serial No. 16,163. Term of patent 3½ years.

To all whom it may concern:

Be it known that I, FRANK J. ARNOLD, a citizen of the United States, residing at No. 622 Mansfield Place, Brooklyn, county of Kings, State of New York, have invented a Button, of which the following is a specification, reference being had to the accompany drawing, forming part thereof.

I claim:

The ornamental design for a button as shown.

FRANK J. ARNOLD.
